UNITED STATES PATENT OFFICE.

AUGUST S. SWANSON, OF WAYZATA, MINNESOTA.

DRIVING CLUB OR MASHIE.

1,334,189.

Specification of Letters Patent. Patented Mar. 16, 1920.

Application filed July 11, 1918. Serial No. 244,436.

To all whom it may concern:

Be it known that I, AUGUST S. SWANSON, a citizen of the United States of America, residing at Wayzata, in the county of Hennepin and State of Minnesota, have invented new and useful Improvements in Driving Clubs or Mashies, of which the following is a specification.

The principal object of the invention is to provide a device of the character mentioned which is simple in construction, which is comparatively cheap and may, therefore, be manufactured and placed within the reach of persons in moderate or poor circumstances.

A further object of the invention is the provision of a driving club or mashie, the handle of which is detachable, the means for such attachment being of a character that will cause the driver to be more firmly tightened on, rather than loosened from the handle when the device is in use.

A further object resides in the provision of a driver reversible for the attachment of two different handles, so that the driver may be used either by a right or a left hand player.

To the exact construction in which it is shown and described the invention is not to be restricted. The right is reserved to make such changes or alterations as the actual reduction to practice may suggest, in so far as such changes or alterations are comprehended in spirit by the annexed claim.

In the accompanying drawings:

Figure 1 is a perspective view of the improved driver.

Fig. 2 is a section on the line 2—2 of Fig. 1.

Fig. 3 is a section on the line 3—3 of Fig. 1.

Referring to the drawings, there is shown a driving head 1 of rectangular shape in plan and having the beveled longitudinal edges 2 and the straight sides 3.

On the top, the head is bored or trained diagonally from opposite ends to provide

the holes 4 and 5, both being internally threaded and the former having right hand threads while the latter is provided with left hand threads. At the hole 5 there is received the threaded end of the handle 6, this handle being for the use of a right hand player, and it is apparent that when the latter strikes a ball with the head, the tendency is to turn the head on the handle which, being secured thereto by left hand threads, tends to tighten the engagement between the head and the handle. The handle received in the hole 4 is identical with the handle 6, but, of course, is provided with right hand threads and is to be used when the device is being employed by left hand persons.

On each of the flat sides 3 there is attached a rubber strip 7 which takes the impact of the ball when it is driven by the head.

These rubber strips are preferably grooved on the head or they may be attached in any other acceptable way.

It is purposed to make the head preferably out of maple and the handles 6 out of hickory; it being contended that with the use of such material and the manner of construction disclosed herein, provides for the making of a driving club of a cheap but effective variety which is the principal object for which the invention is designed.

The invention having been described what is claimed as new and useful is:

A driving club comprising a head of rectangular shape, its upper longitudinal edges being beveled, rubber strips secured on the side faces of the head and covering all the surface thereof between the beveled edges and the bottom face, and a detachable handle for the head, the latter having oppositely disposed diagonally positioned threaded holes in either of which the handle may be engaged, so that either side face of the head may be used as an impact face.

In testimony whereof I affix my signature.

AUGUST S. SWANSON.
